US0D1012643S

(12) **United States Design Patent** (10) **Patent No.:** **US D1,012,643 S**
(45) **Date of Patent:** **** Jan. 30, 2024**

(54) **RATCHET PAWL**

(71) Applicant: **MATCO TOOLS CORPORATION**,
Stow, OH (US)

(72) Inventor: **Darius S. Adibi**, Lyndhurst, OH (US)

(73) Assignee: **MATCO TOOLS CORPORATION**,
Stow, OH (US)

(**) Term: **15 Years**

(21) Appl. No.: **29/820,254**

(22) Filed: **Dec. 21, 2021**

(51) LOC (14) Cl. **08-05**

(52) U.S. Cl.

USPC **D8/25**

(58) **Field of Classification Search**

USPC D8/25
CPC B25B 13/463; B25B 13/465; B25B 13/462
See application file for complete search history.

(57) **CLAIM**

The ornamental design for a ratchet pawl, as shown and described.

DESCRIPTION

FIG. 1 is a top front perspective view of a ratchet pawl;
FIG. 2 is a bottom rear perspective view of the ratchet pawl
illustrated in FIG. 1;

FIG. 3 is a front view of the ratchet pawl illustrated in FIG.
1;

FIG. 4 is a rear view of the ratchet pawl illustrated in FIG.
1;

FIG. 5 is a left side view of the ratchet pawl illustrated in
FIG. 1;

FIG. 6 is a right side view of the ratchet pawl illustrated in
FIG. 1;

FIG. 7 is a top view of the ratchet pawl illustrated in FIG.
1; and,

FIG. 8 is a bottom view of the ratchet pawl illustrated in FIG.
1.

The dash-dash broken lines are included for the purpose of
illustrating portions of the ratchet pawl that form no part of
the claimed design. The dot-dash broken lines define the
bounds of the claimed design and form no part thereof.

1 Claim, 5 Drawing Sheets
